SHOE DISPLAY BOX

Sidney Sigoloff, St. Louis, Mo., assignor to Jayson Shoe Manufacturing Co. Inc., St. Louis, Mo., a corporation of Missouri

Filed Apr. 25, 1966, Ser. No. 2,003

Term of patent 14 years

(Cl. D58—12.6)

FIG. 1 is a front perspective view of a shoe display box showing my new design;

FIG. 2 is a rear perspective view thereof, and

FIG. 3 is a cross sectional view taken on line 3—3 of FIGS. 1 and 2.

I claim:

The ornamental design for a shoe display box, substantially as shown.
